TEMPLATE FOR MEASURING THE ANGLES OF
HUMAN JOINTS

William Kaufman, 540 Brooklawn Ave.,
Bridgeport, Conn.

Filed Aug. 7, 1959, Ser. No. 57,100

Term of patent 14 years

(Cl. D52—6)

Fig. 1 is a side elevation of the template for measuring the angles of human joints showing my new design.

Fig. 2 is an end elevation as seen from the right of Fig. 1.

Fig. 3 is a top plan view.

Fig. 4 is a side elevation showing the opposite side from that illustrated in Fig. 1.

Fig. 5 is an end elevation as seen from the right side of Fig. 4.

I claim:

The ornamental design for a template for measuring the angles of human joints, substantially as shown.
